No 1.025

H. Neidig's Design for Iron Bedsteads for Adults.

Patented July 13. 1858.

Des. 1025

Heinrich Neidig, of New York, N.Y.
Letters Patent, No. 1025, Dated July 13, 1868.

The schedule referred to in these Letters Patent and making part of the same,
To all whom it may concern:

Be it known that I, Heinrich Neidig, of the City, County, and State of New York, have produced a new and ornamental Design for Iron Bedsteads, for Adults, and I do hereby declare that the following is a full, clear and exact description of the same, reference being had to the annexed drawings making part of this specification.

Figure 1, is a side elevation of a Bedstead, with the ornamental designs on the head foot and middle posts represented.

This design consists in producing on the upper ends of cast iron head and foot posts of Bedsteads, in alto-relievo, and bas-relievo, female figures, and at their more central and lower portions, figures of inverted dragons, and oak leaf foliage, and on the middle posts configurations and corresponding oak leaf foliage, in such a manner as to present in their outline and face symmetry of form and ornate finish of design.

The nude female figure B, at the top of the head and foot posts A, is represented as clinging to an oak branch, the foliage C, of which extends downward & in front and behind the same, and so displayed and entwined in relation to this figure and to the inverted tail and back of a dragon D, as it approaches the point where the horizontal rails E, are attached, as to give character and finish to the portion over which they are displayed. The head of the dragon D, is thrown upward with its back extended gracefully upward behind, in the form of a cima-reversa and cima-recta combined, and made to terminate in the ornamental foliage C, and its paws or feet, so arranged, the one flat and the other raised to an acute angle with oak leaves between the two, as to give the increased width to this portion of the casting and cause it to harmonize with the other parts of the design.

Immediately below the extended paw or front leg of the dragon D, are a series of moldings or dentils F, at the top of the portion, upon which the main weight of the corners of the bedstead bear, and below these are formed spaces G, with plain moldings between and below them. The enlarged portions below these openings, are ornamented with egg or semi-spherical projections H, and curved tongues and depressions, and cima-reversa and cima-recta shaped bars I, extending from a band, from which extend downward a series of oak leaves J, below which are formed a series of egg-shaped or semi-spherical projections K, and additional oak foliage L.

The smaller post M, midway between the foot and head posts A, for supporting the middle portion of the bedstead, is ornamented at its upper portion with a head N, in alto-relievo, surrounded by a segment scroll molding O, on the sides of which are formed the ends of oblong panel moldings P, supported by scrolls Q, curving downward and terminating in leaves corresponding with other oak leaves below the head. The spaces between the scrolls and heads are filled in with curved moldings and depressions. The lower portions of these middle posts or

Supports are embellished with a series of oak leaves tastefully displayed over the surface and edges between the scrolls Q, and lower end, one enlarged drop leaf R, being inclosed within the angular corners of an open space made in the casting, and all the configurations harmonizing in style and order, with the corresponding styled configurations on the foot and head posts A.

What I claim as new and desire to secure by Letters Patent, is
Forming bed posts with the configurations and embellishments dis-
posed and arranged to form a new and ornamental design, substantially in the man-
ner before described and represented in the drawings.
